(57) **CLAIM**

The ornamental design of an electrical switch housing, as shown and described.

DESCRIPTION

FIG. 1 is a left side elevation view in accordance with our new design, wherein the right side elevation view is a mirror image;

FIG. 2 is a top plan view thereof;

FIG. 3 is a perspective view thereof;

FIG. 4 is a front elevation view thereof; and,

FIG. 5 is a bottom plan view thereof.

The broken lines shown in the drawing disclosure are for illustrative purposes only and form no part of the claimed design.
